UNITED STATES PATENT OFFICE.

JACOB WILCOX, OF AMLIN, OHIO.

GROUND-ANCHOR.

1,002,350.

Specification of Letters Patent.

Patented Sept. 5, 1911.

Application filed July 5, 1911. Serial No. 636,821.

To all whom it may concern:

Be it known that I, JACOB WILCOX, a citizen of the United States, residing at Amlin, in the county of Franklin and State of Ohio, 5 have invented a certain new and useful Improvement in Ground-Anchors, of which the following is a specification.

This invention relates more particularly to the sort of anchor shown in my patent of 10 the United States No. 972,306 dated October 11, 1910, and can be driven into the ground without preparing a hole for its passage.

The object of the invention is to provide 15 an improved construction of such anchor whereby it may be driven into the ground and turned with great facility to stand at right angles to the stay wire.

The invention is embodied in the instance 20 of it herein shown and described, the features of novelty being pointed out by the claims appended to the description.

In the accompanying drawing—Figure 1 is a view in elevation of that side of the anchor containing the wire attaching lug and 25 also the wire and driving rod applied thereto with portions broken out. Fig. 2 is an edge view of the anchor also showing the wire and driving rod as before mentioned. Fig. 3 is an edge view of the anchor with portions 30 of the wire or link and wire attached showing the position to which the anchor is turned in the ground with reference to the wire portions when the latter are drawn up with sufficient force to effect the change of 35 position of the anchor. Fig. 4 is a plan view of the upper end of the anchor, the wire portions occupying the positions relative thereto indicated in Fig. 3.

In the views the character 5 designates 40 the anchor blade which is made of a suitable piece of hard metal having a pointed or spear shaped penetrating lower end 5^a and a serrated end 5^b. The end 5^b is slightly curved to the side opposite that containing 45 the wire receiving lug said lug being erected on one side or face of the anchor blade. Said lug consists of an approximately semi-conical body having a socket 6^a extending into its base to receive the end of the driving 50 rod and two parallel wings 6^b extending upward from said base adjacent the socket 6^a. The wings 6^b are pierced to receive a pin 7 and on the ends of this pin is secured

by heading the ends of the pin or yoke-link 8 of stout wire or rod. The semi-conical base 55 6^a projects beyond the connections of the yoke with the pin so as to protect said connections from the passing earth when the blade is driven into the ground and the conical projection makes said penetration easier 60 on that account. The main stay wire is connected to the link 8.

The character 9 designates the driving 65 rod. This is a stout bar of metal having an end adapted to enter the socket 6^a.

To drive the anchor into the ground the parts are associated as seen in Figs. 1 and 2 and proper blows of a hammer or mallet administered to the upper end of the driving rod. When the anchor has been driven to 70 the depth desired said rod is withdrawn and the wire drawn upon upward thus causing the anchor blade to turn in the ground and assume a position at right angles to the link 75 and stay wire as seen in Fig. 3. The link 8 facilitates this operation because of the greater freedom of movement of the anchor 80 permitted. In the turning operation the curved upper serrated end of the anchor controls the direction of movement into the position and after this has been accomplished the wire and link can be fixed in 85 tense condition or as may be desired to the structure sought to be braced. The anchor can, of course, be driven into the ground in any direction and depth desired and practicable.

Some slight changes in the form of the parts can be made without departing from the gist of the invention.

What I claim is:

1. An anchor of the kind described consisting of a blade having at one side a wire receiving lug consisting of a semi-conical body having two ribs extending upwardly 95 from its base and a socket in its base to receive a driving rod, and a stay wire connected with said ribs, said base extending laterally beyond the connection of said wire with said ribs.

2. An anchor of the kind described consisting of a blade having at one side a wire receiving lug consisting of a semi-conical body having two ribs extending upwardly 105 from its base and a socket in its base to receive a driving rod, a pin passed through

said ribs and a yoke to receive a stay wire secured to said pin.

3. The combination with an anchor blade having a lug at one side including a tapered portion provided with a socket to receive a driving rod and a portion projecting therefrom to receive a link for the stay wire, of

said link hinged to said last named portion, and a stay wire hingedly connected to said link.

JACOB WILCOX.
